HEAD FOR GOLF CLUBS

Nelson S. Campbell, Greenwich, Conn.

Application September 1, 1945, Serial No. 614,070

5 Claims. (Cl. 273—77)

1

This invention relates to a head for a golf club, more particularly to the method for forming the head on a golf club.

It has been the custom from the earliest days of the game to make certain golf clubs with wooden heads. All clubs were so made for a long time but they were not suitable for some shots and were easily damaged if used to play a ball from a stony "lie."

To meet this difficulty, iron heads were developed for the shorter clubs, but clubs used for the longer shots, which means off the "tee ground" or from good "lies," are still made with wooden heads. These clubs used to be called "drivers," "brassies" and "spoons." Now they are usually designated by numbers 1, 2, 3, etc.

Great improvements have been made in designing, making and finishing these clubs and many of them are works of art to an experienced golfer, but there are definite disadvantages in making these heads of wood.

The good ones are beautifully made. They are well attached to the shafts, the soles are nearly always protected by a shoe of metal attached to the sole with screws, the faces are given durability and greater uniformity by inserts of plastics, also held in place by screws. They are beautifully finished and after they are made they are now usually very carefully matched in weight to a standard, or related to others of a "matched set," by the alteration of lead set into the sole, usually under the metal shoe.

Under this method many fine clubs are produced, but it requires many different operations by skillful, high priced men and necessarily makes the clubs very expensive.

One of the objects of this invention is to provide a better golf club and a golf club at lower cost.

Another object of this invention is to provide a non-metallic golf club head which will be more durable and will have no parts which may work loose.

Another object of this invention is to provide a non-metallic golf club head formed of a material which is tougher and harder than the usual wooden heads which are provided on golf clubs.

Another object of this invention is to provide a golf club head which may be of predetermined standard shape and weight and which may be duplicated exactly in another club.

Another object of this invention is to provide a golf club head by a process sufficiently simple so that it may be made by any well-equipped manufacturer.

2

Another object of this invention is to provide a non-metallic golf club head which will need no metallic shoe on the sole of the club to protect it.

Another object of this invention is to provide a molded golf club head which may be directly molded onto the end of the shaft, such for instance as by molding the head from one of the plastics such as "nylon." "Nylon" is a synthetic plastic more fully set forth in Patent 2,130,948 dated September 20, 1938, and referred to therein as polyamide obtained by condensation polymerization from diamine and dibasic carboxylic acid.

Another object of this invention is to provide a golf club head which may be made in any selected color which is desired.

With these and other objects in view, the invention consists of certain novel features of construction, as will be more fully described and particularly pointed out in the appended claims.

20 In the accompanying drawings:

Fig. 1 is an elevation of a golf club formed in accordance with this invention;

Fig. 2 is a sectional view through a mold illustrating the golf club head as located in the mold and with the shaft extending into the golf club head.

30 In proceeding with this invention, the maker must first adopt the model for the head to be produced. Then, he must work out the weight and balance he wants for each club standard he sets up. He may decide to make few or many, but each must be carefully worked out.

Consider any one model to be made. The steel shaft is now so well made and so carefully graded and controlled that the maker knows the weight of the shaft he decides to use. The weight of the grip to be applied can be known exactly if the grip is made in accordance with the process covered by my current application for a patent on plastic grips, Ser. No. 606,548.

35 The weight of the shaft and grip being known, it is an easy matter to determine what the weight of the head must be to produce the desired weight and balance in the finished club.

40 It is easy to determine what the plastic to be used will weigh when molded to the particular head model to be made. The difference between this weight and the desired head weight shows the amount of weighting, preferably lead, which 50 should be added to make the required finished weight. All this can be determined very exactly.

45 A mold which will exactly produce the head is then made. A chosen shaft is inserted in the mold, together with weighting as required, and 55 the chosen plastic is then molded about the shaft.

With reference to the drawings, 10 designates a golf club shaft which has been provided with a grip 9 and which grip may be formed in accordance with my application, Ser. No. 606,548. The tubular shaft 10 is of steel and is provided with a locking pin 11 which is inserted laterally across the end of the shaft as shown in Fig. 2. A weight, designated generally 12, is supported from the lower end of the shaft 10 by a pin 13. A suitable plug 14 is inserted in the end of the shaft so that the molding material will not enter the hollow shaft 10.

A two-part mold 15 is provided which will be shaped as at 16 to provide a cavity which will be the exact shape and size of the head which it is desired should be formed. The shaft 10 is inserted in this mold, the two parts of which are then locked together through the openings 17. Vent openings 18 are provided adjacent one end of the mold and a gate 19 is provided adjacent the other end for insertion of plastic material 20 into the mold. When all the parts are in place, the plastic material is inserted so as to fill all the cavities in the mold and thus provide the golf club head designated generally 21 in the mold. As in some cases it is impractical to mold material 22 of the shank into the narrow space where the shaft enters the mold, a preforming of the plastic material about this portion of the shaft before insertion into the mold is often desirable. However, this material may be added after molding if desired.

After the material 20 has been molded into the shape of the head 21 about the end of the shaft 10, its locking pin 11, the weighting means 12 and its support 13, the mold is separated and the golf club shaft with its head attached thereto is removed from the mold.

Many plastics are so constituted that they are usable in a mold of this character, an example of which is "nylon." This is sufficiently tough to be found entirely desirable for purposes which are here illustrated. Even though this plastic is molded as a solid mass, it has a desired resiliency and impact strength.

It will be readily apparent that, after one has selected the type of head which he desires, with the exact shape and weight thereof, the manufacturer will choose the type of plastic, make the mold in the desired shape of head, and then cause the plastic to be molded about the end of the shaft. Whether this molding be by pour-casting, compression molding, injection molding or some other form of molding, would depend upon the material which was chosen. The exact choice of the material and the method should be made only after a careful examination of the plastics. If "nylon," known as F. M. 1, is used injection molding will be the more practical form to here adopt.

In some instances it will be desired to place grooves such as 23 on the face of the club head 21, as shown in Fig. 1, and in this case the mold will be correspondingly grooved or ribbed so as to provide the scoring desired.

In some cases, it may be desired to place a plate or shoe on the sole of the club head, and in these

instances the club head would be so shaped so as to receive this facing plate when the same is molded. It is also practical to weight the club head by inserting weights by boring into the material after the same is formed, but in most cases I prefer to mold the weighting material into the club head as herein illustrated, as this saves operations and also more firmly locks the weight in place. It will of course be readily apparent that any markings such as manufacturer's name and model numbers may be molded into the golf club head as the same is formed by merely marking the counterpart of such markings in the mold.

After the molding, which is done in a few seconds, the only work required is surface finishing, which is also quickly done. Excess material from the gate and vents is trimmed off and the surface polished as, for example, with a buffer. Nothing else is necessary unless the manufacturer wishes to rub whitening into any markings he has molded into the surface.

I claim:

1. A golf club having a head with a shank extending therefrom, said shank having a bore therein continuing into said head and straight for its entire depth, a shaft straight for its entire length extending into said bore, a pin of a less diameter than said shaft having an end portion thereof secured in said shaft and extending in a straight line from said shaft and at an angle thereto, a balancing member carried by said pin, said head being one homogeneous mass of molded material completely enveloping said member, pin and the portion of the shaft extending into said head.

2. A golf club as set forth in claim 1 wherein said pin extends through said shaft to project therefrom on either side thereof.

3. A golf club as set forth in claim 1 wherein an additional pin within said head extends through said shaft and projects on either side thereof.

4. A golf club as set forth in claim 1 wherein said shaft is hollow and a plug is inserted in the end of the shaft within said head.

5. A golf club as set forth in claim 1 wherein said shaft is hollow and a plug is inserted in the end of the shaft within said head and said pin extends through said plug.
